(57) **CLAIM**

The ornamental design for a multihead cable connector, as shown and described.

DESCRIPTION

FIGS. 1 and 2 illustrate a top-right perspective view of a multihead cable connector.

FIG. 3 illustrates bottom-left perspective view of a multihead cable connector.

FIG. 4 illustrates a front elevation view of a multihead cable connector.

FIG. 5 illustrates a back elevation view of a multihead cable connector.

FIG. 6 illustrates a right elevation view of a multihead cable connector.

FIG. 7 illustrates a left elevation view of a multihead cable connector.

FIG. 8 illustrates a top plan view of a multihead cable connector; and,

FIG. 9 illustrates a bottom plan view of a multihead cable connector.

The broken line portion of the figure drawings is included to show unclaimed subject matter only and forms no part of the claimed design.

1 Claim, 9 Drawing Sheets
